Primary Examiner—Stella Reid

[57] CLAIM

The ornamental design for a bottle holder, as shown and described.

DESCRIPTION

FIG. 1 is a front elevational view of a baby bottle holder, showing my new design, the rear elevational view being identical thereto;

FIG. 2 is a side elevational view thereof, the opposite side elevational view being identical thereto;

FIG. 3 is a top plan view thereof; and,

FIG. 4 is a perspective view thereof.

The bottom of the bottle holder is plain and unornamented.
